SLICED CHEESE PACKAGE

Robert G. Bush, Green Bay, Wis., assignor to L. D. Schreiber & Company, Inc., Green Bay, Wis.

Filed Sept. 8, 1959, Ser. No. 57,465

Term of patent 14 years

(Cl. D58—2)

FIG. 1.

FIG. 2.

FIG. 3.

FIG. 4.

FIG. 1 is a perspective view of the sliced cheese package, showing my new design;

FIG. 2 is a perspective view of the sliced cheese package shown in FIG. 1 with the package turned over and rotated 180 degrees;

FIG. 3 is a right end view of the article shown in FIG. 1; and

FIG. 4 is a left end view of the article shown in FIG. 1. The essential features of the design reside in those portions shown in full lines on the drawing.

I claim:

The ornamental design for a sliced cheese package, as shown and described.
